UNITED STATES PATENT OFFICE.

BERTHOLD A. LANGE, OF ST. LOUIS, MISSOURI.

EGG CRATE.

Application filed April 7, 1924. Serial No. 704,642.

This invention has reference to egg-cases, such as set forth and described in my United States Patent #1,494,922, granted May 20, 1924, and provides certain specific improvements supplementary to the improvement covered in the aforesaid patent.

The specific object of the present invention is to provide stiffening flanges on the end cell walls of the egg-case so as to stiffen the egg-case on all four sides; the stiffening flange of one strip overlapping the projection of adjacent strips to provide a firm and continuous structure.

In the accompanying drawings forming part of this specification, in which like numbers of reference denotes like parts wherever they occur,

Figure 1 is a plan view of an egg-case filler embodying the preferred form of this invention;

Figure 2 is an elevation of the same;

Figures 3 and 4 are plan views of the flanged blanks used in constructing the subject-matter of Figures 1 and 2;

Figures 5 and 6 are plan views of the plain blanks used in constructing the preferred embodiment depicted in Figures 1 and 2;

Figure 7 is a plan view of an alternative embodiment of this invention;

Figure 8 is an elevation of the same;

Figures 9 and 10 illustrate blanks having co-operating slits of a conventional type which may be used in lieu of the straight slits shown in Figures 1 to 8 inclusive; and

Figure 11 is a plan view of the cutaway flanged blank used in the form depicted in Figures 7 and 8.

The crate filler is composed of a plurality of interlocking partitions 1 and 2 arranged at substantially a right angle to each other and fastened together by any suitable interlocking means at the points where they pass or join each other. This may be accomplished by slits 3 in partitions 1, allowing

partitions 1 to fit down in notches 4 in partitions 2. Otherwise stated, the partitions 1 and 2 are each slit and turned in opposite directions, so that each fits in the slit in the other. Instead of the straight slits 3 and 4,

the well known form of co-operating irregular slits 5, and 6 and 7 may be used, as shown in Figures 9 and 10.

Projections 8 prevent the transmission of shock or jar or slippage to the eggs inserted in the compartments 9, acting as a buffer and preventing telescoping. When the said ex-

tensions or projections 8 are bent or broken the egg breakage is greatly increased. The same should, therefore, preferably be protected by overlapping edges 10, which extend flush with the other edges of the said projections 8. The said flanges or edges 10 may be formed as extensions from the end partitions 1, or from the next-to-the-end partitions 1, or from any one of the intermediate partitions 1.

Such construction as herein-before described has been found too flimsy and to require stiffening. This is accomplished by the arrangement of the transverse members 11, which are arranged at substantially a right-angle to the flanges 10 and may be attached preferably to the end partitions 2. The flanges 10 and 11 will be preferably formed integral with the partitions 1 or 2 from which they spring, but may be otherwise attached thereto.

While the flanges 10 stiffen the crate in one direction, they are entirely inadequate for stiffening the same in a practical manner, so because they do not impart the stability by themselves. They leave the filler in a distinctly collapsible condition, which is very detrimental in egg shipments. It is only by the introduction of the flange or stiffener 11 running crosswise relatively to the flange 10 that the filler assumes the desired and necessary firmness and stiffness. With only the flange 10, and under the vicissitudes of transportation, the eggs will be broken by the shifting in shape of the filler. With the addition of the flange 11, however, and the bearing down of weight upon flanges 10 and 11, considerable rigidity is imparted to the structure as a whole, with the result that it becomes practically immovable.

The usual diaphragm may be used between tiers of fillers.

The stiffening strip or flange 11 preferably overlaps the projections 8 of partition 2, as at 12, and is preferably located on the same face of the crate as flange or flanges 10.

In the preferred form shown in Figures 1 and 2, the flanges 10 and 11 do not extend the full length of the strip, but stop short of so doing at each end a distance equal to the width respectively of flanges 10 and 11, as plainly shown in Figure 1. Only two such flanges at substantially right angles to each other are necessary to stiffen the crate in both directions, but four such flanges as shown in Figures 1 and 2 are preferable, especially

when they are formed on the end partitions.

In the form shown in Figures 7 and 8, only two flanges 10 and 11 at substantially right angles to each other are used, and they are 5 preferably formed on the next-to-the-end partition, although they may be formed on any of the other partitions. The flange 11 extends the full length of the strip, but the flange 10 stops short of so doing at the end 10 adjacent flange 11 a distance equal to the width of flange 11. The inner edges of the flanges 10 and 11 are firmer than their other edges, because their inner edges are attached to the partitions 1 and 2. In the full construction shown in Figure 7, the end of the 15 cut-away flange 10 abuts against the inner side of the flange 11, thus bracing the flanges 10 and 11 together in a continuous structure.

The blank for forming the partitions 1 employed in the form of Figure 1 is depicted in Figure 6, and that for forming the partitions 2 is shown in Figure 5. The blank for forming the partitions having the flanges 10 and 11 of Figure 1 are shown in Figures 3 and 4, 20 respectively; and the blank for forming the flanged partition 10 employing the form of Figure 7 is shown in Figure 11.

This egg-crate filler is adapted to be collapsed for shipment or reshipment and thus 25 to occupy very little space; but when filled with eggs in its pockets the stiffening strips

maintain it in a condition not readily to be collapsed or caused to yield or bend unduly under ordinary pressure.

Having thus described this invention, I 35 hereby reserve the benefit of all changes in form, arrangement, order, or use of parts, as it is evident that many minor changes may be made therein without departing from the spirit of this invention or the scope of the 40 following claim.

I claim:

An egg-crate filler consisting of flexible interlocking strips disposed substantially at right angles to each other to define cells, each 45 having oppositely directed projections extending beyond the outermost strips forming the sides of said filler, each of said outermost strips having projections at the terminals thereof and an overlapping flap therebetween 50 and arranged at the top of each strip, and adapted to be bent to form flanges which abut and rest upon the tops of the several projections, the projections of said outermost strips intersecting at the corners of the fillers being 55 exposed and having their faces substantially flush with the terminal edges of said flanges of said outermost strips.

In testimony whereof I hereunto affix my signature.

BERTHOLD A. LANGE.
